UNITED STATES PATENT OFFICE

JOHN WEBER, OF SCHENECTADY, NEW YORK, ASSIGNOR TO WEBER ELECTRIC COMPANY, OF SCHENECTADY, NEW YORK, A CORPORATION OF NEW YORK

DESIGN FOR AN ELECTRIC-LAMP SOCKET

Application filed June 12, 1930. Serial No. 36,025. Term of patent 14 years.

To all whom it may concern:

Be it known that I, JOHN WEBER, a citizen of the United States, residing at Schenectady, county of Schenectady, State of New York, have invented a new, original, and ornamental Design for Electric-Lamp Socket, of which the following is a specification, reference being had to the accompanying drawing, forming a part thereof.

The figure is a perspective view of an electric lamp socket showing my new design.

The dominant feature of the invention is a plurality of exposed panels disposed around the shell and colored to contrast with the shell. This feature is associated with a plurality of longitudinal lines which present an ornamented surface contrasting with the paneled effect.

I claim:

The ornamental design for an electric lamp socket, substantially as shown and described.

JOHN WEBER.
